CLAIM

The ornamental design for a food storage container as shown and described.

DESCRIPTION

FIG. 1 is a top perspective view of a food storage container showing my new design;

FIG. 2 is a bottom perspective view thereof;

FIG. 3 is a bottom perspective exploded view thereof;

FIG. 4 is a top perspective exploded view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines depict portions of the food storage container that form no part of the claimed design.
